(57) **CLAIM**

The ornamental design for an audio and stand accessory for an electronic device, as shown and described.

DESCRIPTION

FIG. 1 is a front view of the audio and stand accessory for an electronic device according to the present invention.

FIG. 2 is a front view of the audio and stand accessory for an electronic device of FIG. 1 with speakers in an extended position.

FIG. 3 is a rear view of the audio and stand accessory for an electronic device of FIG. 1.

FIG. 4 is a top view of the audio and stand accessory for an electronic device of FIG. 1.

FIG. 5 is a bottom view of the audio and stand accessory for an electronic device of FIG. 1.

FIG. 6 is a left side view of the audio and stand accessory for an electronic device of FIG. 1.

FIG. 7 is a right side view of the audio and stand accessory for an electronic device of FIG. 1.

FIG. 8 is a front perspective view of the audio and stand accessory for an electronic device of FIG. 1 according to the present invention; and,

FIG. 9 is a front view of the audio and stand accessory for an electronic device according to an alternate embodiment. The broken lines showing of electric conduit is for illustrative purpose only and forms no part of the claimed design.
